THUMB TACK

Harold Charles Dowit, 11835 Sheldon St.,
Sun Valley, Calif.

Filed Nov. 12, 1964, Ser. No. 82,576

Term of patent 14 years

(Cl. D54—9)

The essential features of my new design are shown in full lines on the drawings.

I claim:

The ornamental design for a thumb tack, as shown and described.
